Primary Examiner — Cynthia R Underwood(74) *Attorney, Agent, or Firm* — Grandview Law(57) **CLAIM**

The ornamental design for a case for portable electronic computing device, as shown and described.

DESCRIPTION

FIG. 1 is a top perspective view of a case for portable electronic computing device showing our new design.

FIG. 2 is a top plan view thereof.

FIG. 3 is a bottom plan view thereof.

FIG. 4 is a front elevational view thereof.

FIG. 5 is a rear elevational view thereof.

FIG. 6 is a left elevational view thereof.

FIG. 7 is a right elevational view thereof.

FIG. 8 is a top perspective view of a second embodiment of the case for portable electronic computing device showing our new design.

FIG. 9 is a top plan view thereof.

FIG. 10 is a bottom plan view thereof.

FIG. 11 is a front elevational view thereof.

FIG. 12 is a rear elevational view thereof.

FIG. 13 is a left elevational view thereof; and,

FIG. 14 is a right elevational view thereof.

The features shown in broken lines in the drawing figures depict features that form no part of the claimed design.

1 Claim, 6 Drawing Sheets(56)
